STREET DIRECTIONAL SIGN

Myles J. Burke, Jersey City, N. J.

Application August 18, 1949, Serial No. 4,587

Term of patent 7 years

(Cl. D72—1)

To all whom it may concern:

Be it known that I, Myles J. Burke, a citizen of the United States, residing at Jersey City, in the county of Hudson and State of New Jersey, have invented a new, original, and ornamental Design for a Street Directional Sign, of which the following is a specification, reference being had to the accompanying drawing, forming part thereof.

Fig. 1 is a front elevational view of a street directional sign showing my new design.

Fig. 2 is an end view of Fig. 1.

Fig. 3 is an enlarged vertical sectional view taken on the line 3—3 of Fig. 1.

Fig. 4 is a fragmentary enlarged horizontal sectional view taken on the line 4—4 of Fig. 1.

Fig. 5 is a fragmentary enlarged horizontal sectional view taken on the line 5—5 of Fig. 1.

The appearance of the street directional sign

from the back is identical to the front. The appearance of the street directional sign from either end is identical to the other end. The dotted lines shown on the drawing are for illustrative purposes only.

I claim:

The ornamental design for a street directional sign, as shown and described.

MYLES J. BURKE.
